SELF-SHARPENING MECHANICAL PENCIL

Joseph Peter Kohut, New Brunswick, N. J.

Application July 1, 1952, Serial No. 296,690

9 Claims. (Cl. 120—15)

1

This invention concerns mechanical pencils of the type in which mechanism is provided for sharpening the pencil lead. Pencils of this type are particularly useful for mechanical draftsmen who require a sharply pointed pencil to do effective drafting.

According to this invention a lead sharpening blade is incorporated within and as a part of the pencil assembly. A lead holder forming part of the pencil is movable relative to the pencil barrel so that the lead may be retracted into the pencil and sharpened, and then extended to the normal position for drafting, with a minimum of complication and effort.

Objects of the invention are to provide a lead sharpener within a pencil which will form a concentric conical point on the pencil lead, to provide a cavity within the pencil for containing pencil lead scrapings so that they may not spill upon drafting work, and to provide a feeding arrangement for the pencil lead which will not interfere with the operation of the lead sharpener.

For a clear understanding of the details of the invention, reference may be made to the accompanying drawings in connection with the following description. The figures of the drawings show a preferred embodiment of the invention but various modifications may be made to the particular structure shown without departing from the spirit or scope of the invention.

In the drawings wherein similar reference characters designate similar parts,

Fig. 1 is a longitudinal section through a pencil according to the invention.

Fig. 2 is a section on the line 2—2 of Fig. 1.

Fig. 2-a is a section on the line 2—2 of Fig. 1 with the parts in different positions of adjustment from those shown in Fig. 2.

Fig. 3 is a section on the line 3—3 of Fig. 1.

The pencil of the invention comprises a tubular barrel 10 to which a hollow pointed part 11 is secured through a hollow, partly tapered extension 12, the latter being secured to the barrel 10 by means of a bushing 14 which is screwed at one end into the barrel 10 and at its other end into the extension 12.

The upper part of the barrel hollow as shown contains a stem 16 to which a flange 17 is secured, the upper portion of the stem 16 having a slidable seal 18 thereon. The upper end of the stem projects beyond the top of the pencil as at 20 and this part may be knurled to facilitate rotating of the stem by hand and longitudinal movement of the stem within the barrel as will become apparent. The upper end of the barrel is capped as 55

2

at 22, the cap being screwed into the barrel and having an opening 23 therein through which the stem passes. Preferably the stem has one or more projections 24 thereon which pass through slots 25 in the cap. By twisting the stem 16 it may be drawn upwardly from the barrel, the pins 24 passing through the slots 25. When the stem is moved downwardly into the barrel, the pins pass through the slots, the stem may be turned slightly and the stem is then held downwardly in the barrel by engagement of the pins with the under surface of the cap 22. These elements comprise means to lock the holding and feeding means, the stem 16, in operative position in the barrel 10.

The portion of the stem 16 below the flange 17 carries clutch jaws 27 for engagement with the pencil lead 28. A sleeve 30 has tapered engagement with the clutch jaws to force them together and to grip the lead, this sleeve by being urged downwardly by a bushing 32 carrying a flange 33 at its upper end. A compression spring 34 acts between the flanges 17 and 33 and serves to force the clutch jaws 27 inwardly to engage the pencil lead. Bushing 14 is provided with shoulders 36 and 38 so that when the stem is pressed downwardly compressing the spring 34, the ends of the elements 30 and 32 engage the shoulders 38 and 36 so that the jaws 27 are projected therebeyond and disengage from the lead so that the lead is projected downwardly for feeding purposes.

The general push-feed action briefly described is not a specific part of this invention but forms a convenient way for lead holding and feeding. Suitable screw feed devices may be substituted for the mechanism above described if desired.

A spring 40, precompressed to lesser degree than the spring 34, is disposed between the flange 33 and the top of the bushing 14, this spring serving to urge the stem and its associated parts upwardly to press the pins 24 against the inside of the barrel cap 22. It will be seen from the above described construction that the stem along with the lead holding and feeding elements may be jointly withdrawn upwardly when the pins 24 are released from the cap 22 so that the lead 28 may be retracted a considerable distance within the pencil, and also may be projected downwardly so that the point of the lead 28 projects beyond the pencil point 11.

Within the lower end of the bushing 14 are a pair of drillings 42 which are parallel to and spaced from the axis of the bushing. Sharpening blade members 43 are provided, each of which comprise an edged blade 44, the edge of which

3

is slanted as shown at 45, the blade being secured to a pin 46 which is journalled in one of the drillings 42. By this mounting, the blade may be swung about the axis of the pin 46 between positions shown in Figs. 2 and 2-a. The blade member 43 is urged toward the Fig. 2-a position by means of a spring ring 48 occupying a groove 50 formed on the bushing 14, and also occupying notches 52 formed in the pins 46. These notches 52 are so oriented that their inner faces act as cams against which the spring ring 48 bears, as shown in Fig. 3, tending to urge the blade members to the position shown in Fig. 2-a. Stop pins 54 are inserted on the lower end of the bushing 14 to limit the inward swing of the blades 44 so that they will be separated by a very slight distance. When the pencil lead passes between the blades 44, the blades will occupy the position shown in Fig. 2.

To operate the sharpener, the stem 16 is drawn upwardly within the pencil as previously described so that the end of the lead 28 lies above the blades 44. Thereupon, the stem 16 is gently pressed downwardly so that the end of the pencil lead engages the blades 44 which have sprung inwardly to the position shown in Fig. 2-a. The stem 16 is then twirled counter-clockwise (Fig. 2-a) whereupon the lead is shaved to a fine conical point by the blade edges 45. The blades are slant-edged as shown to provide the desired taper of the pointed lead. The shavings of lead are retained in the cavity of the pencil extension 12 occupied by the blades 44. After sharpening, the stem is rotated in the opposite or clockwise direction while gently applying downward pressure on the stem. By this action, the blades 44 are moved apart to the position shown in Fig. 2 due to the frictional engagement of the lead point surface upon the blade edges 45, separating the blade so that the lead may move downwardly between them to project from the lower end of the pencil. Thus, by a simple twisting and axial movement of the stem with respect to the pencil, the pencil lead may be retracted, sharpened, and re-extended from the pencil point to the operating position.

Accumulations of pencil lead scrapings are prevented from leaking from the pencil by the use of a small rubber or flexible plastic washer 56 which is held by metal washers 58 within the pencil extension 12 and between the blades 44 and the point of the pencil. This effectively prevents not only leakage of the lead scrapings but also, jamming of the lead as a result of lead scrapings entering the guide openings in the pencil point 11. Should scrapings work their way upwardly above the bushing 14, leakage of such scrapings is prevented by the slideable seal 18.

It may be noted that the pencil sharpener of this invention is wholly contained within the sealed pencil barrel which distinguishes it from the patents of the prior art where the lead scrapings may fall from the pencil upon drawings or the like upon which the pencil is being used. When it is deemed that a considerable accumulation of lead scrapings is present in the pencil, the lower pencil extension 12 may be unscrewed from the bushing 14 and the scrapings may be emptied, after which the pencil extension 12 is re-assembled on the bushing 14.

The invention is susceptible to several modifications; for instance, the blades 44 may be made of an abrasive material rather than as steel blades. Also, one blade or abrasive element, rather than two, could be used. In such a modifi-

cation, it would be advisable to use a second movable element generally like the blade 44 as a backing up member to oppose the force applied between the lead and sharpening blade to prevent breakage of the lead.

When a screw feed lead feeding mechanism is used, the same sort of sharpening arrangement can be incorporated in a pencil, such adaptation being deemed to lie within the scope of the skilled design. A predominant feature of the pencil of this invention lies in the fact that the lead may be extended through the blades after sharpening by a slight reverse twisting of the stem. In many of the prior art devices the lead must be again retracted to enable retraction of the sharpening devices, causing more complicated operation and the possibility of breaking the lead.

Though one embodiment of the invention is shown, it is to be understood that the invention may be applied in various forms and in various environments. Changes may be made in the arrangements shown without departing from the spirit of the invention. Reference should be had to the appended claims for definition of the limits of the invention.

What is claimed is:

1. A mechanical pencil comprising in combination, a tubular barrel, a lead-holding and feeding device reciprocable and rotatable therein, said device including a stem protruding through the barrel end opposite from the pencil point and including means to hold a pencil lead for extension through the point and for retraction into the barrel, a lead shaving element disposed within the barrel near the pencil point, and means to mount said element in the barrel for lateral swinging movement about an axis parallel to the lead axis into and out of the path of the pencil lead upon movement of the lead within said barrel, said stem, with the device and lead, being rotatable in one direction after lead retraction, to engage the lead with said element to sharpen same after swinging of said element across the path of axial movement of the lead, and being rotatable in the other direction to frictionally engage and swing the element away from the path of axial movement of the lead to enable extension of the lead through the pencil point to writing position.

2. A mechanical pencil and lead sharpener comprising a tubular barrel, means movable within the barrel for holding and feeding a pencil lead through the pencil end, said means including a manually operable feeding device, a lead pointing and sharpening element movably disposed in said barrel near the pencil point for lateral swinging about a pivot parallel to the lead axis, said means being retractable within the barrel to enable a lead held by said holding and feeding means to engage said sharpening element, when swung into the path of said lead said holding and feeding means being rotatable in one direction to engage the sharpening element when swung into the path of said lead and being rotatable in the other direction to rotate said lead to swing, through frictional engagement, said sharpening element from the path of said lead.

3. A mechanical pencil and lead sharpener comprising a tubular barrel, means movable within the barrel for holding and feeding a pencil lead through the pencil end, said means including a manually operable feeding device, a lead pointing and sharpening element movably disposed in said barrel for lateral swinging, said means being retractable within the barrel to en-

able a lead held by said holding and feeding means to engage said sharpening element, said means being rotatable in one direction to engage the sharpening element when swung into the path of said lead with the lead and being rotatable in the other direction to rotate said lead to swing, through frictional engagement, said sharpening element from the path of said lead, said sharpening element comprising a slant-edged blade pivoted for swinging on a pivot whose axis is spaced from and parallel to the barrel axis.

4. A mechanical pencil and lead sharpener comprising a tubular barrel, means movable within the barrel for holding and feeding a pencil lead through the pencil end, said means including a manually operable feeding device, a lead pointing and sharpening element movable disposed in said barrel for lateral swinging near the pencil point, said means being retractable within the barrel to enable a lead held by said holding and feeding means to engage said sharpening element, said means being rotatable in one direction to engage the sharpening element when swung into the path of said lead with the lead and being rotatable in the other direction to rotate said lead to swing, through frictional engagement, said sharpening element from the path of said lead, said sharpening element comprising a slant-edged blade pivoted for swinging on a pivot whose axis is spaced from and parallel to the barrel axis, and elastic means urging said blade edge toward intersection with the barrel axis.

5. A mechanical pencil and lead sharpener comprising a tubular barrel, means movable within the barrel for holding and feeding a pencil lead through the pencil end, said means including a manually operable feeding device, a lead pointing and sharpening element movable disposed in said barrel for lateral swinging near the pencil point, said means being retractable within the barrel to enable a lead held by said holding and feeding means to engage said sharpening element, said means being rotatable in one direction to engage the sharpening element when swung into the path of said lead with the lead and being rotatable in the other direction to rotate said lead to swing, through frictional engagement, said sharpening element from the path of said lead, said sharpening element comprising a slant-edged blade pivoted for swinging on a pivot whose axis is spaced from and parallel to the barrel axis, elastic means urging said blade edge toward intersection with the barrel axis, said holding and feeding means being translatable to extend the pointed lead through the barrel point in an operative position, and means to lock said holding and feeding means in said operative position.

6. A mechanical pencil and lead sharpener comprising a tubular barrel, means movable within the barrel for holding feeding a pencil lead through the pencil end, said means including a manually operable feeding device, a lead pointing and sharpening element movably disposed in said barrel for lateral swinging near the pencil point, said means being retractable within the barrel to enable a lead held by said holding and feeding means to engage said sharpening element, said means being rotatable in one direction to engage the sharpening element when swung into the path of said lead with the lead and being rotatable in the other direction to rotate said lead to swing, through frictional engagement, said sharpening element from the path of said lead, said sharpening element comprising a slant-edged

blade pivoted for swinging on a pivot whose axis is spaced from and parallel to the barrel axis, and elastic means urging said blade edge toward intersection with the barrel axis, said barrel comprising a readily removable sealed point end portion for containing lead scrapings.

7. A mechanical pencil and lead sharpener comprising a tubular barrel, means movable within the barrel for holding and feeding a pencil lead through the pencil end, said means including a manually operable feeding device, a lead pointing and sharpening element movably disposed in said barrel for lateral swinging near the pencil point, said means being retractable within the barrel to enable a lead held by said holding and feeding means to engage said sharpening element, said means being rotatable in one direction to engage the sharpening element when swung into the path of said lead with the lead and being rotatable in the other direction to rotate said lead to swing, through frictional engagement, said sharpening element from the path of said lead, said sharpening element comprising a slant-edged blade pivoted for swinging on a pivot whose axis is spaced from and parallel to the barrel axis, elastic means urging said blade edge toward intersection with the barrel axis, said barrel having a hollow cavity therein for receiving and containing lead scrapings, and sealing means in said barrel between the sharpening element and the pencil end to prevent the inadvertent escape of such scrapings.

8. A pencil comprising a hollow barrel, a conical point at one end thereof, a bushing joining said barrel and point, said bushing having a pivot parallel to the barrel axis and spaced therefrom, a lead sharpening blade mounted on said pivot for swinging across the barrel axis and away from the barrel axis, a stop on said bushing limiting blade movement to prevent overswing beyond the barrel axis, resilient means urging said blade toward engagement with said stop and retaining said blade in assembled position on said bushing, said bushing having a hole therethrough for lead passage, a lead holding and feeding assembly rotatable and reciprocable in said barrel, means on the end of said assembly protruding from said barrel for rotating and reciprocating the assembly in said barrel, and means to lock the assembly in operative position in said barrel, whereby said lead is movable by said assembly between a position extending from the pencil point and a position engaging said sharpening blade, and said lead is rotatable in one direction to be sharpened by said blade and is rotatable in the other direction to swing the blade away from the barrel axis to allow lead projection past the blade through the pencil point.

9. A pencil comprising a hollow barrel, a conical point at one end thereof, a bushing joining said barrel and point, said bushing having a pivot parallel to the barrel axis and spaced therefrom, a lead sharpening blade mounted on said pivot for swinging across the barrel axis and away from the barrel axis, a stop on said bushing limiting blade movement to prevent overswing beyond the barrel axis, resilient means urging said blade toward engagement with said stop and retaining said blade in assembled position on said bushing, said bushing having a hole therethrough for lead passage, a lead holding and feeding assembly rotatable and reciprocable in said barrel, means on the end of said assembly protruding from said barrel for rotating and reciprocating the assembly in said barrel, and means to lock the assembly

in operative position in said barrel, whereby said lead is movable by said assembly, between a position extending from the pencil point and a position engaging said sharpening blade, and said lead is rotatable in one direction to be sharpened by said blade and is rotatable in the other direction to swing the blade away from the barrel axis to allow lead projection past the blade through the pencil point, said blade having a sloped edge and a pivot pin with which said pin 10 pivot comprising a bearing with which said pin is engaged, the pin having a cross-slot formed thereon, and said resilient means comprising a

spring ring embracing part of said bushing and engaging within the cross-slot of said pin.
